UNITED STATES PATENT OFFICE

JOHN SCHURMAN, OF CLEVELAND, OHIO, ASSIGNOR TO YORK ICE MACHINERY CORPORATION, OF YORK, PENNSYLVANIA, A CORPORATION OF DELAWARE

REFRIGERATING APPARATUS

Application filed September 25, 1928. Serial No. 308,287.

My invention relates to refrigerating apparatus of the type in which a spray of cooling liquid is employed for inducing air circulation and lowering the temperature of the air in cold storage rooms or the like. It aims especially to provide a relatively simple structure which is capable of delivering cooled air, free from excessive moisture, thus maintaining in a relatively dry condition, the room in which it is placed.

Other advantages will appear from the following specification when read in conjunction with the accompanying drawing.

In the drawing,—

Fig. 1 is a side view of a spray tube embodying my invention, parts being broken away to show the interior structure;

Fig. 2 is a view taken at right angles to Fig. 1 with parts broken away to show the interior deflector plate;

Fig. 3 is a top plan view;

Fig. 4 is a fragmentary view showing the interior of the air outlet box and its relation to the spray tube;

Fig. 5 is a vertical sectional view of the structure of the surge plate; and

Fig. 6 is a top plan view of the surge plate.

This invention is particularly adapted for use in cooling rooms designed for storing meat and provisions, and when so used the spray tubes may be conveniently mounted on one wall of the room. In the embodiment of the invention shown and described herein, such an arrangement is contemplated. As shown in Fig. 1 of the drawing a spray tube T is mounted on the wall W and held in spaced relation thereto by means of straps 1 fastened to blocks 2.

The spray tube T is made up of a cylindrical body portion 3, a curved elbow inlet portion 4, and a discharge portion 5. The inlet portion 4, having an open end 4^a, is secured to the body portion 3 at 6, so as to form an air and water-tight joint and contains an opening 7 at its top side. Projecting into the opening 7 is a liquid inlet pipe 8 having a nozzle 9 at its lower end. The body portion 3 is apertured near its lower end, to receive an air outlet box 10 secured thereto in any suitable manner as by rivets 11.

The box 10 contains a series of vertically disposed angular eliminators 12 suitably secured to a plate 13 adapted to be carried in an opening 14 in the top of the box 10. These eliminators are held in fixed relation to one another by a plate 15 secured to their lower ends. The front wall of the box 10 is cut away to accommodate a frame structure made up of side pieces 16 riveted to the box 10, and joined together by spaced louvers 17, these louvers being placed at an angle so as to deflect in a downward direction, air currents passing between them. The bottom wall of box 10 slopes inwardly so that the moisture collected from the out-going air may flow to the discharge portion of the tube and mingle with the liquid which collects there.

The discharge portion 5 of the tube T has a restricted portion 18 threaded on the inside to accommodate a liquid discharge pipe 19 which is, in turn, connected to a liquid return header 20. Restricted portion 18 carries two spaced upstanding lugs 21. These lugs are cut away to receive a surge plate 22, carrying two diametrically spaced spacer plates 23 secured thereto, as by brazing, and two diametrically spaced depending lugs 24 riveted thereto. The plate 22, together with spacer plates 23, is apertured at 25 to receive rivets 26 for securing the surge plate 22 and associated parts in fixed relation to the lugs 21. When rivets 26 are driven into position and headed down, the parts occupy the positions shown in Figs. 1 and 5, the plates 23 contacting with lugs 21 and the lugs 24 with the portion 18 so as to leave four rectangular openings 27 between the plate 22 and portion 18. This structure provides a constricted outlet for the tube T, and consequently the liquid entering this tube from the nozzle 9 cannot escape as rapidly as it enters, but accumulates to some depth above the surge plate 22. The collected liquid forms an effective seal for the discharge end of tube T and prevents the escape of air through the liquid discharge pipe 19.

The liquid spray issues from nozzle 9 under considerable pressure and would tend to be thrown into the outlet box 10 and to produce an undesirable accumulation of liquid in 100

this box or air overflow from it. In order to prevent this, a semi-circular deflector plate 28 is secured to the inside wall of the body portion 3 above the opening of the box 10. 5 This deflector plate has an upstanding flange 29 by which it is secured to the body portion 3, so as to hold the plate at a substantial angle with respect to the wall of the tube, and to deflect toward the opposite wall and away 10 from the opening of the box liquid striking it from above.

The outlet box is not far removed from the liquid discharge pipe 19, and when liquid accumulates above the surge plate and is 15 rendered turbulent by the flow of liquid from above, some of this liquid or of the spray might enter the outlet box 10 and escape between louvers 17 into the room. Such a condition is undesirable and would tend to produce a damp room instead of a cool room 20 containing air of the desired moisture content. Such a contingency is avoided by the use of a wiper plate 30 secured to the inside wall of tube T just below the bottom wall of 25 outlet box 10 and in alignment therewith. This plate is in the form of a semi-circular rim having a narrow offset angular flange 31, which projects downwardly toward the liquid outlet. When liquid collects above the 30 surge plate 22 the resulting spray which tends to be thrown over into the box 10 strikes the flange 31 and is deflected back into the tube.

The room containing the installation is 35 preferably constructed with an upstanding barrier 34 in front of the spray tubes so as to form an outlet channel 32 containing a drain 33 for any liquid which may drip from the tubes, due to leaks or condensation.

The operation of the device is as follows:

It will be understood that in practice a plurality of the spray tubes T will be installed in the room to be cooled and that cold liquid or brine will be supplied to the inlet pipes 8 under considerable pressure, preferably at least 25 pounds per square inch. The liquid will be discharged from nozzles 9 in an angular diverging spray, which will pass downward and by injector action draw in air from the room through the inlet opening 4^a. The liquid will be deflected by deflector 28 and will then pass out through openings 27 to discharge pipe 19 and return header 20, which may conveniently return such liquid to the source which supplies the inlet pipes 8.

As the air is drawn in through inlet openings 4^a, it is thoroughly mixed with the liquid spray and its temperature rapidly lowered. When it passes below the deflector 28 it cannot escape through the pipe 19 because it is 65 blocked by the accumulation of liquid above the surge plate 22, and it cannot circulate upwardly because it is opposed by the pressure of the down-flowing liquid from nozzle 9, hence it passes out into outlet box 10, where

the excess moisture is removed by the eliminator plates 12. The discharged air then passes between the louvers 17 which deflect it downwardly into the room where it is warmed and then circulates upwardly to be returned eventually to the inlets 4^a to be cooled again. 70

By the use of this apparatus excess moisture may be removed from the air supplied to the cooler without producing an objectionable drying-out of the products to be cooled. 75 Ceiling condensation is eliminated and it is possible to maintain a satisfactory cooling temperature by supplying cooling brine intermittently. It has been found that when using a liquid pressure of 25 pounds per square inch, very rapid circulation of air can be secured, in some cases as high as 175 feet a minute, at a distance of 34 feet from the spray tubes. 80

Although I have herein shown and described only one form of apparatus embodying my invention, it will be obvious that various changes may be made in the details within the scope of the appended claims without departing from the spirit and scope of my invention. 85

What is claimed is:

1. A refrigerating apparatus comprising a vertically disposed tube having an elbow portion arranged to form a substantially horizontal air inlet; means for supplying a downward current of liquid spray to the inside of said tube to draw air through said inlet; a horizontally disposed air outlet box connected into the wall of said tube near the bottom end thereof; moisture removing means in said box; and means for discharging liquid from said tube. 95

2. A refrigerating apparatus comprising a substantially vertically disposed tube having an angle portion at the upper end thereof; means for supplying a downward current of cooling liquid to the inside of said tube to draw air through said angle portion; an air outlet box connected into the wall of said tube adjacent the lower end thereof; moisture removing means in said box; and means connected to said tube for discharging liquid and cooperating with said spray to prevent the discharge of air therefrom. 105

3. A refrigerating apparatus comprising a vertical tube having an air inlet portion at the top thereof; means for applying a downward current of cooling liquid to the 110 inside of said spray tube; a horizontal air outlet box connected into and supported by the wall of said tube; a series of moisture eliminators in said box; and baffling means inside of said tube for preventing liquid from 115 entering said box. 120

4. Refrigerating apparatus comprising a vertical tube having its top end arranged to form an air inlet; means for supplying a downward current of liquid spray to the in- 130

- side of said tube; an air outlet box near the bottom of said tube; means in said box for removing moisture from the discharged air; a discharge pipe for said tube and connected thereto below said outlet box; means for preventing air from escaping through said discharge pipe; means above said outlet box for deflecting liquid from the opening thereof; and means below said box for preventing liquid from entering said box.
- 10 5. In an apparatus of the class described a vertical tube having an air inlet at the top and an air outlet near the bottom; means for supplying liquid spray to the inside of said tube to draw air through said air inlet; a deflector plate inside of said tube and above said outlet to prevent liquid from entering said air outlet; a restricted liquid discharge orifice at the bottom of said tube; and deflecting means secured to the inside of said tube below said air outlet to prevent liquid from escaping therefrom.
- 15 6. Refrigerating apparatus comprising a vertical tube having an elbow at its top end; means for supplying liquid spray to said tube to draw air through the open end of said elbow and downward in the inside of said tube; means for discharging liquid from the bottom of the tube but preventing the escape of air therefrom; and an air outlet box connected to said tube near the bottom end thereof, said box having a series of vertical eliminator plates for removing excess moisture from the out-going air and a series of louvers for directing the current of air as it leaves said box.
- 20 25 30 35

In testimony whereof I have signed my name to this specification.

JOHN SCHURMAN.

CERTIFICATE OF CORRECTION.

Patent No. 1,762,644.

Granted June 10, 1930, to

JOHN SCHURMAN.

It is hereby certified that error appears in the printed specification of the above numbered patent requiring correction as follows: Page 3, line 26, claim 6, strike out the words "the inside of" and insert same before the word "said" in line 24, same claim; and that the said Letters Patent should be read with this correction therein that the same may conform to the record of the case in the Patent Office.

Signed and sealed this 22nd day of July, A. D. 1930.

- side of said tube; an air outlet box near the bottom of said tube; means in said box for removing moisture from the discharged air; a discharge pipe for said tube and connected thereto below said outlet box; means for preventing air from escaping through said discharge pipe; means above said outlet box for deflecting liquid from the opening thereof; and means below said box for preventing liquid from entering said box.
- 10 5. In an apparatus of the class described a vertical tube having an air inlet at the top and an air outlet near the bottom; means for supplying liquid spray to the inside of said tube to draw air through said air inlet; a deflector plate inside of said tube and above said outlet to prevent liquid from entering said air outlet; a restricted liquid discharge orifice at the bottom of said tube; and deflecting means secured to the inside of said tube below said air outlet to prevent liquid from escaping therefrom.
- 15 6. Refrigerating apparatus comprising a vertical tube having an elbow at its top end; means for supplying liquid spray to said tube to draw air through the open end of said elbow and downward in the inside of said tube; means for discharging liquid from the bottom of the tube but preventing the escape of air therefrom; and an air outlet box connected to said tube near the bottom end thereof, said box having a series of vertical eliminator plates for removing excess moisture from the out-going air and a series of louvers for directing the current of air as it leaves said box.
- 20 25 30 35

In testimony whereof I have signed my name to this specification.
